(57) **CLAIM**

I claim the ornamental design for a foam-dispensing nozzle, as shown and described.

DESCRIPTION

FIG. 1 is a front perspective view of one embodiment of a foam-dispensing nozzle of the present invention.

FIG. 2 is a top view of the foam-dispensing nozzle of FIG. 1, the bottom view of the foam-dispensing nozzle being identical to the top view.

FIG. 3 is a right-side view of the foam-dispensing nozzle of FIG. 1, the left-side view of the foam-dispensing nozzle being identical to the right-side view.

FIG. 4 is a front view of the foam-dispensing nozzle of FIG. 1.

FIG. 5 is a rear view of the foam-dispensing nozzle of FIG. 1.

FIG. 6 is a front perspective view of another embodiment of a foam-dispensing nozzle of the present invention.

FIG. 7 is a top view of the foam-dispensing nozzle of FIG. 6, the bottom view of the foam-dispensing nozzle being identical to the top view.

FIG. 8 is a right-side view of the foam-dispensing nozzle of FIG. 6, the left-side view of the foam-dispensing nozzle being identical to the right-side view.

FIG. 9 is a front view of the foam-dispensing nozzle of FIG. 6; and,

FIG. 10 is a rear view of the foam-dispensing nozzle of FIG. 6.
